(57) **CLAIM**

The ornamental design for a charging case for wireless earphones, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front and right side perspective view of a charging case for wireless earphones showing my new design;

FIG. 2 is a rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front and right side perspective view thereof illustrating the charging case for wireless earphones in an open state; and,

FIG. 10 is a rear and right side perspective view thereof illustrating the charging case for wireless earphones in the open state.

The broken lines in the drawings illustrate portions of the charging case for wireless earphones which form no part of the claimed design.

**1 Claim, 10 Drawing Sheets
